UNITED STATES PATENT OFFICE.

HARRY GILL, OF CHICAGO, ILLINOIS.

METALLIC PACKING-RING.

SPECIFICATION forming part of Letters Patent No. 792,514, dated June 13, 1905.

Application filed March 16, 1905. Serial No. 250,471.

To all whom it may concern.

Be it known that I, HARRY GILL, a citizen of the United States, residing at Chicago, in the county of Cook and State of Illinois, have invented new and useful Improvements in Metallic Packing-Rings, of which the following is a specification.

This invention relates to metallic packing-rings for piston-rods, plungers of pumps, and like engineering construction; and the object thereof is to provide an interchangeable split packing-ring substantially rhomboidal in cross-section, of substantially cone shape, and having a V-shaped cut-away portion and by such construction enabling the necessary take-up to obtain a tight rod, plunger, or the like to be had by the compressing of the ring and the sliding of the ends of the ring toward each other without overlapping.

The invention further aims to provide a metallic packing-ring having a V-shaped cut-away portion substantially conical in contour, rhomboidal in cross-section, durable, interchangeable, efficient in its use, readily introduced and removed, and comparatively inexpensive to manufacture.

With the foregoing and other objects in view the invention resides in the construction of the split metallic packing-ring hereinafter more specifically described, illustrated in the accompanying drawings, which form a part of this specification, and particularly pointed out in the claims hereunto appended.

In describing the invention in detail reference is had to the accompanying drawings, wherein like reference characters denote corresponding parts throughout the several views, and in which—

Figure 1 is a sectional elevation of a stuffing-box, showing the adaptation of a metallic packing constructed in accordance with this invention. Fig. 2 is a perspective view of a metallic packing-ring constructed in accordance with this invention; and Fig. 3 is a section on the line 3-3, Fig. 2, showing the rhomboidal configuration of the ring in cross-section.

A packing-ring in accordance with this invention may be constructed of any suitable metal or metals, preferably from an admix-

ture of copper, tin, antimony, and lead, in any desirable proportions, which is machined or otherwise formed into an interchangeable and compressible split composite metallic packing-ring substantially conical in contour having a V-shaped cut-away portion and rhomboidal in cross-section. 55

The ring, which is imperforate, is indicated by the reference character 1 and, as before stated, is substantially conical in contour, 60 rhomboidal in cross-section, as shown in Fig. 3, and is slotted therethrough, so as to provide a V-shaped cut-away portion converging from the outer to the inner end thereof, as indicated by the reference character 2, said V-shaped cut-away portion clearly shown in Fig. 2. 65

Owing to the constructing of the ring in a conical manner, when a plurality of the rings are used they are readily interchangeable, and 70 owing to providing the ring with the V-shaped cut-away portion it is very readily placed in position around the part to be packed. A further function derived from the providing of the cut-away portion is that when the ring 75

is compressed there will be no overlapping of the ends of the ring, which would be the case if the slit or cut-away portion was of different contour. Then, again, it enables the ends of the ring to slide or move toward one another 80 during the compression of the ring in such a manner that there can be no overlapping of the ends, as the edges of the ends will move in such a direction as to prevent such overlapping. Owing to constructing the ring 85

rhomboidal in cross-section, an excellent bearing for both the side of the stuffing-box and piston-rod or plunger is obtained, as will be readily seen by reference to Fig. 1, as the outer edge and inner edge of the ring snugly 90 surround the piston-rod or plunger and engage the inner face of the stuffing-box. Consequently it insures an absolutely perfect joint. It will furthermore be stated that owing to providing the ring with the V-shaped 95 cut-away portion or slit the necessary take-up can be had without any danger of the ends of the ring overlapping, and thereby insuring an absolutely perfect joint.

Referring to Fig. 1 of the drawings, 3 de- 100

notes the stuffing-box, having a boss 4 supported in the lower end thereof. 5 denotes a gland extending into the top of the box. 6 denotes adjusting-screws for the gland, which 5 engage in the offsets 7 and 8, carried, respectively, by the stuffing-box 3 and gland 5. 9 denotes the piston-rod, 10 a series of superposed and interchangeable packing-rings constructed in accordance with this invention 10 and which are arranged within the stuffing-box 3 and surround the piston-rod 9, and 11 denotes a split packing interposed between the series of packing-rings 10 and the gland 5.

Having thus fully described my invention, 15 what I claim as new, and desire to secure by Letters Patent, is—

1. An imperforate metallic packing-ring substantially conical in contour and having a V-shaped cut-away portion converging from

the outer to the inner end, thereby splitting 20 the ring.

2. An imperforate metallic packing-ring substantially conical in contour, rhomboidal in cross-section and having a V-shaped split converging from its outer to its inner end. 25

3. A metallic packing-ring substantially conical in contour, rhomboidal in cross-section and having a V-shaped split extending entirely therethrough, said split converging from its outer to its inner end. 30

In testimony whereof I have hereunto set my hand in presence of two subscribing witnesses.

HARRY GILL.
